(57) **CLAIM**

The ornamental design for a tracking device wallet, as shown and described.

DESCRIPTION

FIG. 1 is a front, top and right side perspective view of a tracking device wallet, showing my new design;

FIG. 2 is a front view of the article shown in an opened configuration;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings illustrate the portions of the tracking device wallet, which form no part of the claimed design.

The dot-dot-dash broken lines representing stitching are part of the claimed design.
